UNITED STATES PATENT OFFICE

171,380

ELECTRIC LAMP BASE

David Borowitz, Chicago, Ill., assignor to Bradley Manufacturing Company, Chicago, Ill., a corporation of Illinois

Application July 22, 1953, Serial No. 26,074

Term of patent 3½ years

(Cl. D48—20)

To all whom it may concern:

Be it known that I, David Borowitz, a citizen of the United States and a resident of Chicago, Illinois, have invented a new, original, and ornamental Design for an Electric Lamp Base, of which the following is a specification, reference being had to the accompanying drawing, forming a part thereof.

Fig. 1 is a front elevational view of an electric lamp base embodying my new design; and

Fig. 2 is a top plan view thereof.

The dominant features of my new design lie in the portions shown in full lines.

The broken lines indicating the lamp socket of Fig. 1 have been omitted from Fig. 2 for convenience of illustration.

I claim:

The ornamental design for an electric lamp base, substantially as shown and described.

DAVID BOROWITZ.
